DESIGN FOR A STOKER

Floyd D. Yarick, Detroit, Mich.

Application December 23, 1938, Serial No. 81,970

Term of patent 14 years

To all whom it may concern:

Be it known that I, Floyd D. Yarick, a citizen of the United States, residing at Detroit, in the county of Wayne and State of Michigan, have invented a new, original, and ornamental Design for Stokers, of which the following is a specification, reference being had to the accompanying drawings, forming part thereof.

I claim:
The ornamental design for a stoker, as shown.

FLOYD D. YARICK.
